RESTAURANT BUILDING

Jimmie L. Jones, Salt Lake City, Utah, assignor to Ute
Indian Tribe of the Uintah and Ouray Reservation,
Uintah County, Utah

Filed May 2, 1972, Ser. No. 249,751

Term of patent 14 years

Int. Cl. D25—03

U.S. Cl. D13—1 B

FIG. 1

FIG. 2

FIG. 4

FIG. 5

FIG. 6

FIG. 7

FIG. 1 is a perspective view of the building from one side, showing my new design;

FIG. 2 is a similar view, from the opposite side thereof;

FIG. 3 is a top plan view thereof;

FIG. 4 is a view of the building from one side, indicated by the arrow (FIG. 4) in FIG. 3;

FIG. 5 is a similar view of another side, indicated by the arrow (FIG. 5) in FIG. 3;

FIG. 6 is a view of the building from another side, indicated by the arrow (FIG. 6) in FIG. 3; and

FIG. 7 is a view of the building from another side, indicated by the arrow (FIG. 7) in FIG. 3.

I claim:

The ornamental design for a restaurant building, substantially as shown.
